(57) **CLAIM**

The ornamental design for a mobile phone holder, as shown and described.

DESCRIPTION

FIG. 1 is a bottom and rear perspective view of a mobile phone holder in an open position;

FIG. 2 is a top and front perspective view of the mobile phone holder in the open position;

FIG. 3 is a front view of the mobile phone holder in the open position;

FIG. 4 is a rear view of the mobile phone holder in the open position;

FIG. 5 is a left side view of the mobile phone holder in the open position;

FIG. 6 is a right side view of the mobile phone holder in the open position;

FIG. 7 is a top view of the mobile phone holder in the open position;

FIG. 8 is a bottom view of the mobile phone holder in the open position;

FIG. 9 is a top and front perspective view of the mobile phone holder in a closed position;

FIG. 10 is a top and front perspective view of the mobile phone holder in a semi-open position; and,

FIG. 11 is a left side view of the mobile phone holder in the semi-open position.
